UNITED STATES PATENT OFFICE.

HENRY L. DISMER AND NORMAN MIRFIELD, OF DAVENPORT, IOWA.

MATTRESS-SEWING MACHINE.

1,166,193.

Specification of Letters Patent. Patented Dec. 28, 1915.

Application filed May 20, 1914. Serial No. 839,723.

To all whom it may concern:

Be it known that we, HENRY L. DISMER and NORMAN MIRFIELD, citizens of the United States, and residents of the city of Davenport, county of Scott, and State of Iowa, have invented certain new and useful Improvements in Mattress-Sewing Machines, of which the following is a specification.

10 Our invention relates to sewing machines and more specifically to that class thereof designed for use especially in the manufacture of mattresses in forming the roll or bead provided, as is known, at the edge of a mattress.

15 The object of our invention is the production of a sewing machine as mentioned which will be of durable and economical construction, one which will be of an adjustable nature so as to permit of rolls or beads of various sizes being formed, and one which will be efficient in use.

Other objects will appear hereinafter.

20 With these objects in view our invention consists in the combinations and arrangements of parts hereinafter described and claimed.

25 The invention will be best understood by reference to the accompanying drawings forming a part of this specification, and in which,

30 Figure 1 is a substantially central vertical section of a sewing machine embodying our invention, Fig. 2 is a section taken on substantially line 2—2 of Fig. 1, Fig. 3 is a section taken on substantially line 3—3 of Fig. 2, Fig. 4 is an enlarged detail section illustrating the escapement mechanism coöperating with the work supporting platform 13 of the machine, Fig. 5 is a detail section taken on substantially line 5—5 of Fig. 1, Fig. 6 is a view of the upper portion or head of the machine looking from the line 6—6 and in the direction of the arrows of Fig. 1, Fig. 7 is a detail section taken on substantially line 7—7 of Fig. 1, and Fig. 8 is a detail section taken on line 8—8 of Fig. 1.

35 The preferred form of construction as illustrated in the drawings comprises a supporting element or table 10 provided with a base or supporting legs 11. Mounted upon the upper side of table 10 are longitudinally extending spaced parallel rails 12. Mounted 40 above the table 10 is a work supporting platform 13 equipped at its under side with

channel rollers 13' which engage with rails 12 as is clearly shown in the several views.

Coöperating with the table 10 is a weight 14 equipped at its upper side with a channel 60 pulley 14' which rests loosely in a bight formed in a cord or flexible element 15 between the secured end 16 of said cord and a channel pulley 17 over which said cord passes. The opposite end 18 of cord 15 is 65 rigidly secured to the outer end of platform 13. The arrangement is such, as will be seen, that, with the platform positioned at the end of the table 10 as shown in the several views, the weight 14 will be supported 70 in an elevated position and will exert a downward pressure or gravity force upon the bight in cord 15 engaged by pulley 14' which will tend to move the platform 13 toward the opposite end of table 10. With 75 this arrangement then it will be seen that, upon release of said platform, the same will be automatically advanced or moved along the table 10. Such movement of said platform is intermittently arrested by escapement mechanism comprising a rack or plurality of spaced stops 19 secured centrally upon the under side of said platform.

Arranged upon the upper side of table 10 is a bar 20 which is mounted for reciprocating movement transversely of rack 19 between guides 21. Carried by the member 20, as clearly shown in Fig. 4, are engaging

80 fingers 22 and 23 pivotally fastened to the member 20 at 24 and 25 respectively. Co- 85 operating with said fingers 22 and 23 are compression springs 26 and 27 respectively which normally hold said fingers against stops 28 and 29 respectively. Said springs 90 are interposed as shown between said fingers 95 and stops 30 and 31, the latter also serving as means of limiting the pivotal movement of said fingers when the same are rocked against the tension of said springs. The

95 arrangement is such that, upon reciprocation of the member 20, the fingers 22 and 23 will alternately engage with the teeth of rack 19. When the finger 23 is moved from engagement with said rack and the finger 22 is moved into engagement therewith, (the 100 latter, when moved into engagement, being in the dotted line position shown in Fig. 4), the influence of weight 14 upon the platform 13 will overcome the tension of spring 26 causing rocking of the finger 22 to the full 110 line position thereof as shown in Fig. 4.

Upon return movement of the member 20,

in which the finger 22 will be moved out of engagement with the rack 19 and the finger 23 moved into engagement therewith, the latter finger will simply serve to hold 5 the table in the position to which the same has advanced when under the domination of finger 22.

Immediately upon the release of finger 22, the same will be returned to its normal position by the spring 26 and, upon the succeeding reciprocation of the member 20, will engage another tooth of rack 19 so as to permit of another advance of the platform 13 immediately upon movement of the finger 15 23 out of engagement with said rack. Thus it will be seen that the movement of the platform upon the table 10 will be intermittently arrested or interrupted, said platform gradually stepping along said table in the 20 reciprocatory movement of the member 20. The finger 23 is pivotally mounted and a spring 27 is provided for coöperation therewith so as to afford means of effecting intermittent stepping or feeding of the platform 25 in the opposite direction if desired. When this is done the cord 15 needs only to be passed around the opposite side of pulley 17 and the end 18 thereof connected with the opposite end of the platform. When this is 30 done it will be seen that the functions of fingers 22 and 23, as just described will be reversed.

Arranged above the platform 13 is a sewing element consisting of a head or supporting body 32 which is supported in angular position relative to said platform by a base member 33 rigidly supported upon table 10. The head 32 is provided at one side with a curved or arcual foot 34 which is in slidable dove-tail connection with a channel 35 of corresponding form provided in the adjacent side of the upper end portion of base 33. One side 36 of the channel 35 is removably secured in position, being held in operative 45 position by means of hand screws 37. The arrangement is such, as will be seen, that head 32 is so supported as to permit of angular adjustment thereof, such adjustment being permitted when screws 37 are loosened. 50 After adjustment of said head, the same is locked in its position of angular adjustment by simply tightening said hand screws.

Provided at the front side of head 32 is a substantially circular housing 38 in which 55 is arranged a needle bar 39 mounted for reciprocatory movement. At the lower end of said needle bar is provided a needle 40 of conventional construction. Coöperating with said needle is a presser foot 41 supported in 60 operative position by means of presser bar 42 which is rigidly secured at its upper end to housing 38. Actuation of needle bar 39 is effected through the medium of a link 43 which connects said bar with a crank 44 provided at one end of a shaft 45 mounted

in suitable bearings provided in head 32. One end of the shaft projects exteriorly and is provided with a channel pulley 46 around which passes an endless belt 47, the latter also passing around a channel pulley 48 of 70 an electric motor 49. Guide rollers 50 co-operate with the belt 47 in the passage thereof between the pulleys 46 and 48. Also co-operating with said belt is a pair of pulleys 51 provided at the upper end of a pivoted 75 lever 52 with which cooperates a helical tension spring 53. The pulleys 51, lever 52 and spring 53 constitute a slack-taking-up device which permits of angular adjustment of the head 32, as before mentioned, without effecting the operative connection between the driving motor 49 and the shaft 45, as will be readily understood. The shaft 45 is equipped at its outer end also with a hand wheel 54 to permit of manual rotation thereof 80 when desired.

Formed in the shaft 45 is a crank 55 with which connects the upper end of a link 56. The lower end of link 56 is connected with a crank 57 provided at one end of a shaft 90 58 mounted in suitable bearings provided in the lower end of head 32. At the opposite end of shaft 58 is provided a rotary shuttle 59 of conventional construction designed to co-operate with the needle 40 in the sewing 95 operation as will be readily understood by those skilled in the art.

Supported at the upper end of head 32 is a spool of thread 60, the thread 61 in unwinding from said spool passing through a 100 tension device 62 and thence through perforations provided in the opposite sides of an inverted substantially U-shaped member 63 fastened to the upper end of housing 38. In its passage from one side of member 63 to the other the thread 61 passes also through the perforated upper end of a finger 64. The lower end of said finger 64 is equipped with an eccentric band 65 which embraces an eccentric 66 secured to shaft 45 110 as clearly shown in Fig. 7. The arrangement is such that, during rotation of said shaft, the finger 64 will be vertically reciprocated causing the thread 61 to be drawn or looped downwardly in order to effect unwinding thereof from the spool 60, said finger constituting a thread feeding mechanism as will be readily understood by those skilled in the art. After passing from the member 63 the thread 61 passes through the upper end of needle bar 66 and thence to the eye at the lower end of the needle. 115

Provided upon the shaft 58 is also a cam 67 which engages against an arm 68 fulcrumed at 69 in the lower end of the head 120 32. Said arm is held in constant contact with the cam 67 by means of a compression spring 68'. Also fulcrumed at 69 is a depending arm 70 which is releasably locked to the broadened lower end of arm 68 by 130

- means of thumb screw 71 passing through segmental slot 72 provided in said end of arm 68. With this arrangement it will be seen that an operative connection is established between arms 68 and 70 so that upon oscillation of the former through rotation of cam 67, said arm 70 will be simultaneously oscillated. The releasable connection between said arms 68 and 70 permits of angular adjustment of the latter relative to the former in order to operatively position the same for the performance of its function set forth in the following, after angular adjustment of the head 32.
- 15 The lower end of arm 70 engages with a slot 73 provided in an extension plate 74 adjustably connected with the rearward end of member 20 by means of thumb screw 74', said screw passing through an elongated slot 20 75 provided in the plate 74 so as to permit of relative longitudinal adjustment of the latter as will be readily understood. The table 10 is slotted at 76, as clearly shown in Figs. 4 and 5, in order to accommodate the lower 25 end of arm 70, as will be readily understood.
- With the construction set forth it will be seen that an operative connection is established between the sewing element and the escapement mechanism coöperating with the 30 platform 13, this connection being however adjustable by reason of the adjustable connection of arms 68 and 70 and plate 74 and member 20 so as to maintain this operative connection in the angular adjustment of the 35 head 32.
- In the operation of the machine the mattress A which it is desired to operate upon is positioned upon the platform 13 as clearly 40 shown in dotted lines in Fig. 1, with the platform positioned at the end of the table 10 shown in the several views. Guide or stop flanges 77 project upwardly from the table 10 for coöperation with said mattress to determine the position thereof relative to 45 the sewing element as will be readily understood. The bases 78 of the members 77 are adjustably connected with the table 10 by means of thumb screws 79 which engage with elongated transversely extending slots 50 80 provided in said base portions. With this arrangement it will be seen that adjustment of the inner or objective edge of the mattress toward or from the sewing element is readily effected by simply adjusting the 55 position of members 77. Upon operation of the motor 49 it will be seen that the needle 40 will pierce the adjacent edge portion of the mattress so as to result in the formation of a roll or bead. The mattress carrying platform 13 will be gradually advanced or fed 60 along the table 10 past the sewing element resulting in the gradual sewing of the mattress edge. It is of course understood that the periods of movement of the platform 13 65 will occur when the needle 40 is out of en-
- gagement with the mattress. Through the angular adjustment afforded the head 32 and by reason of the adjustable mounting of the guide members 77 it is clear that a roll or bead of any size within reasonable range 70 may be formed upon the mattress. Also it will be seen that the sewing operation is entirely automatic which will result in the production of a roll or bead of uniform size throughout its length. 75
- While we have illustrated and described the preferred form of construction for carrying our invention into effect, this is capable of variation and modification without departing from the spirit of the invention. 80 We, therefore, do not wish to be limited to the precise details of construction set forth, but desire to avail ourselves of such variations and modifications as come within the scope of the appended claims. 85
- Having described our invention what we claim as new and desire to secure by Letters Patent is:
1. A machine of the class described comprising a movable work supporting element; 90 an angularly disposed sewing element arranged adjacent one edge of said supporting element; means for intermittently moving said work supporting element relative to said sewing element, said last mentioned means comprising means adapted normally to move said work supporting element in one direction; and escapement mechanism for intermittently arresting the movement of said element, substantially as described. 100
  2. A machine of the class described comprising a movable work supporting element; 105 an angularly disposed sewing element arranged adjacent one edge of said supporting element; means for intermittently moving said work supporting element relative to said sewing element, said last mentioned means comprising means adapted normally to move said work supporting element in one direction; and escapement mechanism 110 comprising a pair of reciprocatory engaging members for intermittently arresting the movement of said supporting element, substantially as described.
  3. A machine of the class described comprising a movable work supporting element; 115 an angularly disposed sewing element arranged adjacent one edge of said supporting element; means for intermittently moving said work supporting element relative to said sewing element, said last mentioned means comprising means adapted normally to move said work supporting element in one direction; means for intermittently arresting the movement of said supporting 120 element, said means comprising a rack; and escapement mechanism coöperating with said rack; substantially as described.
  4. A machine of the class described comprising a movable work supporting ele- 130

ment said last mentioned means comprising a plurality of spaced stops on said supporting element; escapement mechanism co-operating with said stops; an operative connection between said sewing element and said escapement mechanism; and means for operating said sewing element, substantially as described.

12. A machine of the class described comprising a movable work supporting element; an angularly disposed sewing element arranged adjacent one edge of said supporting element and angularly adjustable relative to the latter; means for intermittently moving said work supporting element relative to said sewing element, said last mentioned means comprising means adapted normally to move said work supporting element in one direction; means for

intermittently arresting the movement of 20 said supporting element, said last mentioned means comprising a plurality of spaced stops on said supporting element; escapement mechanism co-operating with said stops; an operative connection between said sewing 25 element and said escapement mechanism adjustable in accordance with the angular adjustment of said sewing element; and means for operating said sewing element, substantially as described.

In testimony whereof we have signed our names to this specification in the presence of two subscribing witnesses.

HENRY L. DISMER.
NORMAN MIRFIELD.
